UNITED STATES PATENT OFFICE.

IRVING F. NILES, OF PLAINFIELD, NEW JERSEY, ASSIGNOR TO POTTER PRINTING PRESS COMPANY, OF PLAINFIELD, NEW JERSEY, A CORPORATION OF NEW JERSEY.

PRINTING-PRESS.

1,119,861.

Specification of Letters Patent.

Patented Dec. 8, 1914.

Application filed January 29, 1911. Serial No. 605,407.

To all whom it may concern:

Be it known that I, IRVING F. NILES, a citizen of the United States, and a resident of Plainfield, in the county of Union and 5 State of New Jersey, have invented certain new and useful Improvements in Printing-Presses, of which the following is a specification.

My invention has particular reference to 10 the mechanism for shifting one of the members of the printing couple with respect to the other so as to trip or untrip the impression, and the general objects of the invention are to improve and simplify this mechanism and to reduce it to the fewest possible 15 number of parts.

To these ends the invention resides in combining with the members of a printing couple, means for shifting one of the members with respect to the other, this shifting means carrying abutment members so disposed that when one of said members is acted upon, the shifting means will be caused to trip the impression and when the other 25 abutment member is acted upon, the shifting means will be caused to untrip the impression. Suitable actuating means are provided for acting upon the abutment members, and suitable devices are employed 30 for positioning the actuating means to engage one or the other of the abutments. This positioning device or devices may be manually controlled or, if desired, may be automatically controlled, according as to 35 whether the stock is present or absent at the proper time. In a preferred form of the invention, the shifting means is in the form of toggle links and so disposed on opposite sides of the center of support of such link 40 that when one of the abutments is acted upon, the toggle will be broken and when the other abutment is acted upon, the toggle will be made. These movements of the toggle will be utilized to accomplish the shifting of one member of the couple with respect to the other, and so when one (or both) 45 of the members is a cylinder, eccentric journal bearings may be used to which the toggles may be directly connected.

Various other objects and features of my invention will appear as the specification proceeds.

In the accompanying drawings I have illustrated several preferred embodiments of my invention, but it will be understood 55 that various changes and modifications may be made therein without departing from the spirit and scope of the invention.

In the drawings: Figure 1 is a view of my invention as applied to what is known as an 60 "offset press," parts of the press being broken away and shown more or less diagrammatically. Fig. 2 is a view of a slightly modified form of the invention.

Like reference characters refer to like 65 parts throughout the several views.

Referring first to that form of the invention illustrated in Fig. 1, the printing couple is shown here as composed of an offset or blanket cylinder 1 and an impression cylinder 2. This blanket cylinder is also known as a transfer cylinder, since it receives a transfer in ink of the matter to be printed from the form cylinder 3. For the purpose of shifting one of the members of 75 the printing couple to trip or untrip the impression, the impression cylinder is here shown as carried in eccentric journal bearings 4 to which bearings are pivotally connected at 5, one end of a pair of toggle links 80 6 and 7. The other end of the toggle is pivoted at 8 to the frame 9 or other stationary part of the machine, and the two toggle links are pivoted together at 10. (It will be understood that the toggle and the eccentric bearing, or such other shifting devices as may be employed, may be duplicated at the other end of the cylinder, the said pivot 8 being for this purpose a rock shaft.

The means for shifting the members of the printing couple are provided with abutments or abutment members 11, 12, which abutment members are so disposed that when one of them is acted upon, the impression will be tripped, and when the other member is acted upon, the impression will be untripped. When toggles are employed as a means for shifting the members of the printing couple, these abutment members may be carried by one of the toggle links—that one of the links (7) which is mounted upon the frame or other stationary part and in such a case the two abutments are disposed on opposite sides of the center of pivotal

support for the toggle link, in other words on opposite sides of the rock shaft.

The actuating means for engaging the abutments to make or break the toggle may vary. In Fig. 1 this actuating means consists of a member 13 supported at one end by a swinging link 14 and having its other or free end provided with oppositely arranged shoulders 15 for engagement with the two abutments. The free end of the actuating member is disposed in between the two abutment members so as to be capable of engagement with either, and the end of the member may normally rest upon the lower abutment (11) so as to be slidably supported thereon. When the free end of the actuating member is so supported, the abutment members may be in the form of rolls, as indicated in Fig. 1, so as to reduce the friction. The actuating member is reciprocated by suitable means such as a cam 16 engaging a cam roll 17 carried by the swinging lever 14. This cam is timed to rotate in unison with the members of the printing couple. This may be done by means of the intermeshing gears 18 and 19 on the impression cylinder and cam shaft 20 respectively.

The devices for positioning the actuating means may vary. In Fig. 1 this positioning device is manually controlled and consists of a pedal 21 connected by a rod 22 to the actuating member. A yielding part may be placed in this connection, such as the spring 23, having a bearing between the shoulder 24 on the rod and the lug 25 on the actuating member. If, when the pedal is depressed, the actuating member is on the limit of its out stroke, as in Fig. 1, the spring will store power and give the actuating member a further lift at the end of its inward stroke, so as to bring the uppermost shoulder 15 into engagement behind the abutment 12. The positioning pedal 21 after being depressed, may be locked in such position by means of a pivoted latch 26 which is controlled by a supplementary pedal 27.

In the operation of that form of the device shown in Fig. 1, the sheets are fed from the feed-board 28 by automatic or other means to the impression cylinder 2. So long as the feeding of stock is uninterrupted, the parts will remain substantially as in Fig. 1, the actuating member simply reciprocating idly back and forth. When any interruption in the feed occurs, or when it is desired to trip the impression for other reasons, the foot pedal 21 will be depressed thereby elevating the actuating member into position for engagement with the upper abutment 12. When the uppermost shoulder 15 on the actuating member engages with the upper abutment 12, the said member will in its outward reciprocation, rock the toggle link

7 about the center of support 8, thereby breaking the toggle and turning the eccentric bearings so as to shift the cylinder 2 away from the other member of the printing couple. By the use of the latch 26 the parts may be allowed to remain in this tripped position as long as desired. But if the latch is not used, when the pressure is removed from the foot pedal 21, the actuating member will lower of its own weight until the lowermost shoulder 15 comes into engagement with the lower abutment 11. Then, upon the outward stroke of the actuating member, the toggle link 7 will be turned back to its original position, thereby making the toggle and restoring the impression.

The operation of that form of the invention shown in Fig. 2 is substantially the same as just described. Here also the pivotally mounted toggle link 7 carries the two abutments 11 and 12 which are disposed on opposite sides of the center of support of the link. In this case, however, the actuating means consists of two reciprocating members 29 and 30, the first having a shoulder 31 for engagement with the abutment 11, and the other having a shoulder 32 for engagement with the abutment 12. The members 29 and 30 may be conveniently supported from a lever 33 pivoted to rock upon the center 34, and for the purpose of imparting the necessary reciprocating movement to the members 29 and 30, a cam 35 may be provided for engagement with the cam roll 36 carried by the lever 33. From what has already been said, the tripping and untripping function of these parts will be readily understood without further description. The means for positioning the actuating means in this second form of the invention consists preferably of a pivoted lever 37 having connection with the reciprocating members 29 and 30 through the agency of the rocker arms 38 and 39 and the connecting rods 40 and 41. In this instance also the machine may be manually controlled, in which case the tripping and untripping of the impression could be effected by shifting the lever 37. I have, however, shown in this view a form of automatic trip which is controlled according to the presence or absence of stock at the proper time. This controlling mechanism as here shown consists of a pivoted finger 42, coöperating with the drop roller 43, and a rocking lever 44 pivoted to rock on the center 45, and connected to the lever 37 by means of the rod 46. The lever 44 may be caused to rock by any suitable means, such as the cam 47 engaging the cam roll 48 connected to the arm 44 by means of an extension 49.

The finger 42 is disposed in the line of the sheet feed (indicated by the dotted line 130

50) and when no stock is present at the time it should be, the feeler finger will assume the dotted line position in Fig. 2. At this time the rocking arm 44 will have been turned by 5 the cam 47 to the position indicated in dotted lines at which time the heel of the feeler finger will fall down in front of the arm 44 and prevent it making the return stroke. The lever 37 and the arms 38 and 39 will 10 be thereby held in that position indicated in the dotted lines, so that the lever 30 will be shifted to bring the shoulder 32 thereon into position for engagement with the abutment 12. When the cam 35 now rocks the arm 33, 15 the member 30 will be lifted, thereby rocking the toggle link 7, thus breaking the toggle and interrupting the impression. If now the stock is fed in at the proper time, the point of the feeler finger will be depressed by 20 the stock to the full line position in Fig. 2, so that the heel of the finger will not interfere with the rocking movement of the arm 44. Therefore, when the arm 44 is rocked back to its full line position, the actuating 25 member 29 will, through the connections described, be shifted so as to engage the abutment 11, and then the cam 35, acting through the roll 36 upon the lever 33, will cause the actuating member 29 to rock the toggle link 30 and restore the impression. In addition to 35 the automatic control, the tripping and untripping of the impression will also be controlled manually, as by means of a handle 51 having connection with the arm 52 which is 40 directly connected to the rocking arm 44. It will be obvious that when this handle is depressed, as shown in dotted lines, the impression will be tripped the same as when the heel of the feeler finger drops into engagement with the rocking arm 44.

What is claimed, is:

1. In a printing press, a printing couple comprising a cylinder and a member coöperating therewith, movable bearings for said cylinder, toggles comprising links pivoted at one end upon the frame of the press and connected at the other end to the bearings, abutment members carried by the pivotally supported links and disposed on opposite sides of the center of support of said links, an actuating device mounted to reciprocate between said abutment members and having shoulders for engagement with the abutment members, means for reciprocating the actuating device, and means for positioning the actuating device to engage one or the other of the abutment members.

2. In a printing press, a printing couple embodying a cylinder and a member coöperating therewith, eccentric journal bearings for the cylinder, toggle links pivotally connected between the eccentric journal bearings and a stationary part of the press, abutment members carried by the toggle link 65 which is pivoted upon the stationary part

and disposed on opposite sides of such center of pivotal support, actuating means having a reciprocating movement, and means to position the actuating means to engage one or the other of the abutment members. 70

3. In a printing press, a printing couple embodying a cylinder and a member coöperating therewith, eccentric journal bearings for the cylinder, toggle links connected at one end to the eccentric bearings and at the other end pivotally supported on a stationary part of the press, abutments carried by the said pivotally supported links and arranged in opposite sides of the centers of support of such links, an actuating device 80 mounted to reciprocate in between the said abutments and formed with shoulders for engagement with said abutments, means for reciprocating the actuating device, and means for positioning said actuating device 85 to engage one or the other of the abutments.

4. In a printing press, a printing couple embodying a cylinder and a member coöperating therewith, eccentric journal bearings for the cylinder, toggles comprising links pivoted at one end upon the frame of the press and connected at the other end to the bearings, abutment members carried by the pivotally supported links and disposed on opposite sides of the center of support of 90 said links, an actuating device mounted to reciprocate between said abutment members and having shoulders for engagement with the abutment members, means for reciprocating the actuating device, and means for positioning the actuating device to engage 95 one or the other of the abutment members.

5. In a printing press, a printing couple embodying a cylinder and a member coöperating therewith, eccentric journal bearings for the cylinder, toggles comprising links pivoted at one end upon the frame of the press and connected at the other end with the eccentric bearings, spaced abutments carried by the pivotally mounted links disposed on opposite sides of the centers of support of said links, an actuating device having shoulders for engagement with the said abutments, said actuating device having its one end normally resting upon one of the abutments, a swinging link supporting the opposite end of the actuating device, a cam for imparting a reciprocating movement to the actuating device, and means for shifting the outer end of the actuating device to bring 110 it into engagement with the other of the abutments. 115

6. In a printing press, a printing couple embodying a cylinder and a member coöperating therewith, movable bearings for said cylinder, a rock shaft, connections from said rock shaft to the movable bearings, abutment members carried by the rock shaft on opposite sides thereof, an actuating member mounted to reciprocate in between said 120 125 130

abutment members and, provided with shoulders on opposite sides thereof, means for reciprocating said member, and means for positioning the actuating member to cause one or the other of the shoulders thereon to actively engage with the respective abutment member.

Signed at Plainfield in the county of Union and State of New Jersey this twenty-third day of January A. D. 1911.

IRVING F. NILES.
